UNITED STATES PATENT OFFICE.

FREDRICK C. SCHMIDT, OF ST. LOUIS, MISSOURI, ASSIGNOR OF ONE-FOURTH TO JAMES CORNELL, OF ST. LOUIS, MISSOURI.

GRAIN-DOOR.

1,179,869.

Specification of Letters Patent. Patented Apr. 18, 1916.

Application filed September 26, 1914. Serial No. 863,752.

To all whom it may concern:

Be it known that I, FREDRICK C. SCHMIDT, a citizen of the United States, residing at St. Louis, in the State of Missouri, have invented 5 certain new and useful Improvements in Grain-Doors, of which the following is a specification.

This invention relates to improvements in doors and more particularly to grain car 10 doors.

The object of my invention consists in providing a grain car door designed for use in cars where the door frames are of varying size to overcome the present short- 15 coming of nailing the doors upon the door frames of the grain cars.

A further object of my invention consists in providing a grain car door which shall possess the important characteristics of simplicity of construction, efficiency in service 20 cheapness of manufacture as well as capable of fitting door frames of various sizes without the necessity of nailing the doors in position or of encumbering the same with any 25 extraneous parts.

A still further object of my invention consists in providing a grain car door embracing a minimum number of parts designed to facilitate the assembling of the door in 30 position upon the car as well as to assure the removability of the same with the necessity for but slight labor.

With the above and further objects in view my invention consists in the combination, arrangement, and details of construction disclosed in the drawings and specification, and then more particularly pointed out in the appended claims.

Referring now to the drawings which are 40 merely illustrative of my invention, Figure 1 is a front elevation of my invention, while Fig. 2 is a rear elevation thereof. Fig. 3 is a horizontal section taken on the line 3—3 of Fig. 1. Fig. 4 is a vertical cross-sectional 45 view taken on the line 4—4 of Fig. 1. Fig. 5 is a detail perspective of one of the latching dogs.

Referring further to the drawings wherein similar reference characters designate 50 similar parts throughout the respective views, 1 designates the door frame in general which may be of any approved design

or construction. Adapted to this door frame is a door made of a substantially rectangular plank preferably of wood in which are arranged, at opposite ends, the carriers designated 3 and 4 respectively. The door 2 is to be of any satisfactory size and will be placed in position opposite the door frame by suitable latch mechanism now to be described.

Each of the carriers 3 and 4 is composed of a side plate 5 and an end plate 6 preferably extending beyond the edges of said plate 5. A housing 7 is secured upon both 65 the side plate 5 and end plate 6 and is formed upon its side 8 with a slot 9 through which projects a latching dog 10, said dog consisting of a hook-shaped member formed upon its bill 11 with two series of oppositely-disposed notches 12 and 13 upon its opposite edges. A transverse pin 14 is secured to each of said dogs at its end opposite to its bill, said pin being secured intermediate its ends upon said dog. Extending 75 in the housing 7 opposite either edge of the slot 9 is an elongated rack bar 15. A pair of these rack bars is provided with the alining notches 16 in which the pin 14 is adapted to be placed or lodged.

It will be understood that the rack bars 80 15 will be spaced from the side wall or plate 5 to provide a suitable space 17 to enable the dog 10 to be introduced into and readily removed from the housing. The carriers 3 85 and 4 will preferably be made of metal as well as the dog 10 to increase the strength of the same in a very substantial manner.

The door proper 2 will be formed at opposite ends with the longitudinal slots 18 in 90 which are adapted to slide and fit the housings 7 of the carriers in such a way that the housings will be completely embedded in the door 2, being made of uniform width therewith, so that the side plates 5 may 95 bear against one side of the door proper 2 and the end plate 6 may bear against one end of said door, being made of equal dimensions therewith.

Formed in the opposite sides 19 and 20 100 of the door proper 2 are the recesses 21 extending into the jambs thereof. These recesses will be of sufficient depth to accommodate the serrated bills of the dogs 10.

The pillars 22 span said recesses 21 and are vertically disposed opposite the same, being thinned out intermediate their ends.

From the foregoing construction it will be observed that when it is desired to mount the door proper 2 in position against the door frame the door will be placed against the door frame so as to overly the inner side thereof. The carriers 3 and 4 will have been fitted in the door before the latter is applied against the frame. By forcing the dogs 10 inwardly of the slots 9 a proper distance they may be freely manipulated and slid in said slots in such a way that the bills of said dog will project in said recesses 21 and then, after the pin 14 of the dog shall have been placed in the notches 16, said bills 11 may be caught upon the pillars 22, any of the notched parts 13 of said dogs engaging with said pillar in the conventional way. There is a click 23 pivotally mounted in each of the recesses 21 adapted to engage any of the other notches 12 formed in the bills of said dogs 10 whereby to lock said dogs effectively against movement. When the two dogs shall thus have been locked upon the pillars 22 it will be seen that the door will be held in closed position against the door frame. By releasing the clicks 23 from locked position the dogs 10 may be detached from the pillars and incased in said housings 7. By moving the dogs longitudinally in slots 9 the dogs may be separated the proper distance apart to engage with the door jambs of varying sized door frames.

Numerous modifications may be resorted to in practice without departing in principle from the details of construction herein disclosed.

What I desire to protect and secure by Letters Patent is:

1. In combination, a door frame, a door formed with longitudinal slots, carriers removably inserted into said slots and including side plates adapted to abut the door surface and housings adapted to project through the door, said housings being formed with slots, dogs adapted to be inserted through slots and locked within respective carriers, and means for locking the free extremities of the dogs to said door frame.

2. In combination, a door frame, a door formed with longitudinal slots, carriers adapted to be inserted into said slots and including side and end plates adapted to contact with the door surface and housings, the latter being formed with slots, racks in each housing, locking dogs, a notched bill formed on one extremity of each of said dogs, a pin formed on the other extremities of said dogs and adapted to be inserted through respective housing slots for engagement with respective racks, and means for locking the bill extremities of the dogs to adjacent portions of the door frame.

3. In combination, a door frame a door formed with longitudinal slots, carriers removably mounted in said slots and including housings lying flush with one surface of the door, slots being formed in the housings, racks contained in each housing adjacent the slot edges, arcuate dogs formed at opposite extremities with notched bills and transverse pins, the latter being adapted to be inserted through said housing slots for engagement with respective racks, and means carried upon opposite door frame portions for engaging the notched bills of said dogs in locking the door to its frame.

4. In combination, a door frame, a door provided with longitudinal slots, carriers removably mounted in said slots and including housings adapted to lie flush with one surface of the door, said housings being provided with slots, racks adjacent the edges of each housing slot, locking dogs formed at one extremity with transverse pins, and at the other extremity with a bill doubly notched on opposite edges, said pins being insertible through said slots for engagement with respective housing racks, and means carried by said door frame for locking engagement with both notched edges of each dog bill.

5. In combination, a recessed door frame, a door, carriers removably arranged within said door and including housings formed with slots, racks in each housing adjacent the slots, dogs adapted to be inserted through said slots for an adjustable locking engagement with said racks, notched bills formed on said dogs to project into said door frame recesses, and means spanning said recesses for an adjustable locking engagement with the dogs projecting thereinto.

6. In combination, a recessed door frame, a door, carriers removably inserted into said door, racks supported within each carrier, locking dogs adapted to project into each carrier for an adjustable locking engagement with said racks, each of said dogs being formed with an arcuately turned extremity, notched on both edges, and adapted to project into the recessed portions of said door frame, a pillar spanning each recessed frame portion for engagement with the notches of one side of respective dogs, and means carried by said pillars for removably engaging the notches on the other side of respective dogs.

7. In combination, a door frame provided with a pair of opposite recesses, a door formed with longitudinal slots, a carrier adapted to be removably inserted into each slot, racks supported within each carrier, locking dogs adapted to project into respective carriers and recesses, a pin carried by each dog for engagement with the racks of the corresponding carrier, a bill formed upon the opposite extremities of each dog

with opposite series of notches, a pillar spanning each frame recess and adapted to adjustably engage the notches of one series of the corresponding dog, and a click pivotally carried by each pillar for engagement with the opposite notch series of the corresponding dog.

In testimony whereof I affix my signature in presence of two witnesses.

FREDRICK C. SCHMIDT.
